UNITED STATES PATENT OFFICE.

WALTER H. BOWES, OF STAMFORD, CONNECTICUT.

MACHINE FOR POSTMARKING AND CANCELING MAIL.

1,365,886.

Specification of Letters Patent. Patented Jan. 18, 1921.

Application filed February 12, 1919. Serial No. 278,551.

To all whom it may concern:

Be it known that I, WALTER H. BOWES, a subject of the King of Great Britain, residing at Stamford, in the county of Fairfield 5 and State of Connecticut, have invented certain new and useful Improvements in Machines for Postmarking and Canceling Mail; and I hereby declare that the following is a full, clear, and exact description 10 thereof, reference being had to the accompanying drawings, which form part of this specification.

This invention relates to machines for postmarking and canceling mail, but it is 15 also adaptable to other machines in which an intermittently rotatable member is employed to operate upon articles, (such as letters, sheets of paper, checks and the like) fed therewith; and therefore, while I will 20 describe an embodiment of the invention particularly constructed and designed for use in connection with stamp canceling and postmarking machines, it is to be understood that the invention is susceptible of other 25 applications in the art and is not limited to the particular machine described.

The objects of the invention are: to provide novel improved frictional clutch means for driving the die carrier intermittently 30 from a continuously driven shaft; to provide the die carrier with upper and lower frictional members; to provide novel means for regulating the frictional pressure or amount of friction between the die carrier 35 friction clutch members and the positively driven friction clutch members; to enable the driven friction clutch members to be also used as auxiliary feeding means coöperating with the impression roller to feed 40 the article past the die-carrier; to enable the stop and tripping mechanism to be disposed above the table if desired; and to simplify and improve the construction of parts, make them reliable and efficient in 45 operation, and enhance the practical speed of operation of the machine.

I will explain one practical embodiment 50 of the invention, illustrated in the accompanying drawings, to enable others familiar with the art to understand, adapt and use the same. In the claims are summarized the essential features of the invention and the various novel constructions and combinations of parts therein, for all of which 55 protection is desired.

In said drawings:

Figure 1 is a vertical sectional elevation of part of the printing mechanism of a postmarking and stamp canceling machine embodying the invention. 60

Fig. 2 is a diagrammatical top plan view thereof.

Fig. 3 is a detail sectional view on line 3—3, Fig. 2.

Fig. 4 is a detail sectional view on line 4—4, Fig. 2.

In the construction indicated in the drawings, (Fig. 2), I is the impression roller; P the die-carrier or printing roller coacting therewith; R the so-called trip-pressure- 70 roller, and R' the coacting so-called trip-feed-roller; all of which are shown as relatively arranged and adapted to operate substantially as in the so-called "Universal" stamp canceling and postmarking machines, 75 which are well known and therefore do not require further detailed description herein.

The impression roller I is shown as mounted upon a shaft 1, which may be journaled in a swingable bracket 1^b and 80 may be driven by any suitable means; a universal joint connection 1^c is shown between the lower end of shaft 1 and a driven shaft 1^a below; which shaft 1^a may be driven by gearing (not shown); the construction indicated being such as is used in the said "Universal" machines. 85

Mounted adjacent the shaft 1 and parallel therewith is a shaft 2 which may be journaled in a bushing 2^a in a part T' on 90 the table T, and in a bushing 2^b which may be supported on the part T' in any suitable way. The bushings or bearings 2^a and 2^b however should be in exact parallelism so that the shafts 1 and 2 will be parallel; 95 but the shaft 1 is preferably movable laterally toward or from the shaft 2.

As shown the bushing 2^b is supported in the inner end 2^c of a bracket 2^d which is 100 adjustably attached to parallel upright studs t t rising from and fast to the part T' adjacent the shaft 2. The bracket 2^d is preferably bored and split as shown to facilitate its engagement with studs t t, and is removably fastened thereto by a clamping bolt 2^e 105 tapped through the slit end of the bar, as indicated in Figs. 1 and 2.

Mounted upon the shaft 2 between the bushings 2^a and 2^b is the printing roller or member, which, in the construction indi- 110

cated, (and in the Universal machine referred to) includes a postmarking and stamp canceling die. This printing roller or member, in the construction shown, comprises a parti-cylindric die 3 which may be provided as usual with suitable postmarking and stamp canceling printing surfaces on its outer periphery. This die 3 is rotatably mounted upon the shaft 2, and it is preferably provided with upper and lower hub extensions 3^a and 3^c, which extensions are respectively provided, opposite the ends of the die, with friction members or disks 3^b and 3^d respectively. All the parts (3, 3^a, 3^b, 3^c, 3^d) might be formed integral but preferably the die and friction disks are formed separately and rigidly connected to an axial sleeve in any suitable way, as indicated in the drawings, so that they are practically unitary.

On the shaft 2 below the disk 3^d is non-rotatably secured a cupped friction member 4; as shown the hub of this member 4 is pinned to the shaft 2, as indicated at 4^a. This friction member is preferably chambered on its upper surface to receive the opposed friction disk 3^d, and the exterior of the peripheral flange 4^b of member 4 lies opposite the periphery of the impression roller I and is adapted to co-act therewith in forwarding articles, such as letters, indicated at M in Figs. 1 and 2.

This friction member 4 carries a friction washer 4^a (of any suitable material, preferably cork) which directly contacts with the lower side of the friction disk 3^d on the lower end of the die.

Slidably but non-rotatably mounted upon the shaft 2 above the die and upper friction disk 3^b, is a cupped friction member 5 (similar to member 4) having a recess on its under side for the reception of the opposed friction disk 3^b; and the exterior of the depending peripheral flange 5^a of member 5 is adapted to co-act with the opposed surface of the impression roller I in feeding the article M past the die, as indicated in Figs. 1 and 2.

The friction member 5 carries a friction washer 5^b, (of any suitable material, preferably cork), which is adapted to contact with the upper surface of the opposed friction disk 3^b on the die hub. As shown in Fig. 3 the friction member 5 is slidably but non-rotatably connected with the shaft 2 by means of a pin 5^a passed through a transverse slot 2^c in the shaft; and the shaft 2 is bored out above the slot 2^c and into the threaded upper end of this bore is tapped an adjustable screw bolt 6, which is provided with a locking nut 6^a on it above the shaft 2. Between the inner end of this bolt 6 and the pin 5^a is interposed a helical expansion spring 6^c, and preferably the lower end of spring 6^c is connected to a pin 6^d

which is guided in a contracted part of the bore and has its lower end rounded and contacting with bar 5^a to impart pressure of the spring thereto.

By adjusting the bolt 6 in the shaft 2 the degree of pressure exerted by the friction members 5 and 4 upon the friction disks 3^b and 3^d can be adjusted to regulate the amount of frictional pressure under which the die is normally urged to rotate with the shaft 2.

The shaft 2 may be driven continuously by any suitable means; or as in the "Universal" machine, by suitable gearing connected with its lower end, but not shown; but the printing roller P or die 3 in such stamp canceling and postmarking machine is only permitted to rotate intermittently, or once for each article M that is fed past it. For this purpose any suitable automatically operating die stopping and releasing devices may be provided.

The printing roller or die 3 is shown as provided with a stop roller 11^a, which may be conveniently mounted on the stud or pin 3^a by which the printing or marking surfaces are detachably attached to the die (in the usual manner) not necessary to herein show or explain. Said roller 11^a is adapted to engage a stop roller 12^a on the long arm 12 of a rocking stop lever pivoted on a pin 12^b attached to bracket 2^a, and the short arm 12^c of lever 12 may be connected by a link 14 to the arm 15^x of the trip finger 15 which is adapted to project into the path of the incoming articles M, as indicated in Fig. 2, so as to be successively tripped or rocked thereby.

The trip finger is shown as pivoted at 15^b on one end of a lever 16, pivoted in turn at 16^c on an arm 16^x projecting from bracket 2^a, said lever being normally held by a spring 16^b against a stop 18 on arm 16^x. The short arm 12^c of lever 12 is normally held against a stop 13^a by a spring 12^b connected to said arm 12^c and to the bent end of an adjustable rod 12^c which is supported in a bore in the bracket 2 and can be locked in any adjusted position, by means of a thumb screw 12^a (see Fig. 4).

This tripping mechanism is generally constructed like, and is intended to operate, substantially as shown and described in Frederick E. Poor's Patent No. 1,309,655, July 15, 1919, and therefore needs no further detailed explanation herein; but in the present case all the operative parts of the trip are shown as above the table and readily accessible, and are bodily removable and replaceable with bracket 2^a.

In operation the trip finger 15 is actuated by each incoming article M in time to cause the stop 12^a to release the die 3 at the proper moment. The die is always urged to rotate with the continuously rotating shaft 2 by

- the friction members 5 and 4 engaging the opposed friction members 3^b, 3^d on the die 3 so whenever the trip releases the die, the latter instantly takes up rotation with the shaft 2 and makes one complete rotation, but is then stopped by the roller 11^a again engaging stop roller 12^c which, during such rotation of the die, is returned to position to engage roller 11^a and arrest the die.
- 10 Upon the hub 3^c of the die, between the disk 3^a and the die 3, may be placed a pinion 7, which engages with a similar pinion 7^a on the upper end of a shaft 7^b which has a worm 7^c on its lower end engaging the actuating gear 7^d of a suitable counting mechanism C, indicated but not shown, by which each rotation of the die 3 is registered, and thus the number of impressions or operations of the die 3 are counted.
- 15 The die and friction members should be provided with suitable ducts to conduct lubricant to the bore of the die, and all parts requiring lubrication; such ducts being well known, and within the province of a mechanic to supply, I have not illustrated same in detail herein.
- 20 What I claim is:
1. In mechanism of the character specified, the combination of a rotating impression roller, a printing member, and friction members at opposite ends of the printing member adapted to drive the printing member and coöperate with the roller in feeding articles past the printing member.
- 25 2. In mechanism of the character specified, the combination of a rotating impression roller, a die, and combined friction and feed disks at opposite ends of the die adapted to drive the die and coöperate with the roller in feeding articles past the die.
- 30 3. In mechanism of the character specified, the combination of a rotating impression roller, a printing member having friction surfaces at its opposite ends; friction members opposite said surfaces and in constant engagement therewith; means for positively rotating the friction members, and means for permitting the printing member to rotate with the friction members.
- 35 4. In mechanism of the character specified, the combination of a rotating impression roller, a die, friction disks connected with opposite ends of the die, and positively driven friction members at opposite ends of the die respectively engaging the opposed friction disks on the die.
- 40 5. In mechanism of the character specified, the combination of a rotating impression roller, a die, friction disks connected with opposite ends of the die, and positively driven friction members at opposite ends of the die, respectively engaging the opposed friction disks on the die, means for arresting the die, and means for releasing
- 45 the die.
- 50 6. In mechanism of the character specified, the combination of a rotating impression roller, a printing member, having friction surfaces at its opposite ends adapted to coöperate with the roller in feeding articles past the printing member; friction members opposite said surfaces; means for positively rotating the printing member, and means for permitting the printing member to rotate with the members.
- 55 7. In mechanism of the character specified, the combination of a rotating impression roller, a die, friction disks connected with opposite ends of the die, positively driven friction members at opposite ends of the die respectively engaging the opposed friction disks on the die, and adapted to coöperate with the roller in feeding articles past the die.
- 60 8. In mechanism of the character specified, the combination of a rotating impression roller, a die, friction disks connected with opposite ends of the die, positively driven friction members at opposite ends of the die respectively engaging the opposed friction disks on the die, and adapted to coöperate with the roller in feeding articles past the die; means for arresting the die, and means for releasing the die.
- 65 9. In mechanism of the character specified, the combination of a printing member having friction surfaces at opposite ends, and friction members respectively continually operatively engaging the opposed friction surfaces; means for positively rotating the friction members; and means for permitting the printing member to rotate with the members.
- 70 10. In mechanism of the character specified, the combination of a printing member having friction surfaces; disks at opposite ends; friction members continually in cooperative engagement with the friction surfaces; means for positively rotating the friction members; means for stopping the printing member, and means for permitting the printing member to rotate with the friction members.
- 75 11. In mechanism of the character specified, the combination of a die having friction surfaces at its opposite ends, friction members at opposite ends of the die respectively continually engaging the opposed friction surfaces; means for positively rotating the friction members; means for stopping the die, and means for permitting the die to rotate with the friction members.
- 80 12. In mechanism of the character specified, the combination of a rotating impression roller, a die having combined friction and feeding disks at its opposite ends adapted to coöperate with the roller in feeding articles past the die; friction members co-operating with the disks; means for posi-
- 85 90 95 100 105 110 115 120 125 130

- 5 13. In mechanism of the character specified, the combination of a rotating impression roller, a die, friction disks connected with opposite ends of the die, friction members at opposite ends of the die respectively
- 10 engaging the opposed friction disks on the die and adapted to coöperate with the roller in feeding articles past the die; means for positively rotating the friction members, means for stopping the die and article operated means for releasing the die so it can rotate with the members.
- 15 14. In mechanism of the character specified, a driven shaft, a die rotatably mounted thereon having friction surfaces at its opposite ends, friction members connected with said shaft and rotating therewith and in continuous operative engagement with said surfaces to cause the die to rotate; means for arresting the die; and means for releasing the die.
- 20 15. In mechanism of the character specified, a driven shaft, a die rotatably mounted thereon provided with friction surfaces at its opposite ends, friction members connected with said shaft and rotating therewith and engaging said surfaces to cause the die to rotate, said friction members being adapted to assist in feeding articles past the die; means for arresting the die, and means for releasing the die for each article passing the same, substantially as described.
- 25 16. In mechanism of the character specified, an impression roller, a driven shaft beside the roller, a printing member rotatably mounted thereon provided with friction surfaces at opposite ends, friction members connected with said shaft and rotating therewith and engaging said surfaces to cause the printing member to rotate, said friction member having circular peripheral flanges adapted to coact with the impression roller to feed articles past the printing member, substantially as described.
- 30 17. In mechanism of the character specified, a driven shaft, a printing member rotatably mounted thereon provided with a friction surface at each end; a pair of friction members attached to said shaft at opposite ends of the printing member and respectively continuously engaging the friction surfaces, and means for yieldingly pressing the friction members toward each other to regulate the friction between the opposed friction surfaces.
- 35 18. In mechanism of the character specified, an impression roller, a driven shaft beside the roller, a die rotatably mounted thereon provided with friction disks at its opposite ends, friction members connected with said shaft and rotating therewith and
- 40 engaging said disks to cause the die to rotate, said friction members having circular peripheral flanges adapted to coact with the impression roller to feed articles past the die; means for arresting the rotation of the die; means for releasing the die for each article passing the same, substantially as described.
- 45 19. In mechanism of the character specified, a driven shaft, a die rotatably mounted thereon provided with a friction surface at each end; a pair of friction members attached to said shaft at opposite ends of the die and respectively continuously engaging the friction surfaces and means for yieldingly pressing the friction members toward each other to regulate the friction between the opposed friction surfaces with means for arresting the die, and article actuated means for releasing the die for each article passing the same, substantially as described.
- 50 20. In mechanism of the character specified, a driven shaft, a printing member rotatably mounted thereon, provided with friction surfaces at opposite ends, friction members connected with said shaft and rotating therewith and continuously engaging said surfaces to cause the printing member to rotate; with a spring for pressing one of the friction members toward the other, and means for adjusting the spring to regulate the pressure on the opposed friction surfaces.
- 55 21. In mechanism of the character specified, a driven shaft, a printing member rotatably mounted thereon, friction surfaces at opposite ends of and connected with the printing member; friction members connected with said shaft and rotating therewith and engaging said surfaces to cause the die to rotate; a spring in the shaft for pressing one of the friction members toward the other, and an adjustable bolt tapped into the shaft and engaging the spring to regulate the pressure of the opposed friction surfaces.
- 60 22. In mechanism of the character specified, a driven shaft, a printing member rotatably mounted thereon, friction disks on opposite ends of the printing member, a pair of friction members attached to said shaft at opposite ends of the printing member and respectively engaging the friction disks, said friction members being hollow to receive said friction disks; and means for yieldingly pressing the friction members toward each other to regulate the friction between the opposed friction surfaces.
- 65 23. In mechanism of the character specified, a driven shaft, a die rotatably mounted thereon, friction disks at opposite ends of the die, a pair of friction members attached to said shaft at opposite ends of the die and respectively engaging the friction disks, said friction members being hollow to receive said

friction disks; and means for yieldingly pressing the friction members toward each other to regulate the friction between the opposed friction surfaces; with means for 5 arresting the die at the end of each rotation thereof and article controlled means for releasing the die for each article passing the same, substantially as described.

24. In mechanism of the character specified, the combination of an impression roller 10 and means for rotating same, a driven shaft beside the impression roller, a printing member rotatably mounted thereon provided with a friction surface at each end; a pair of friction members attached to said shaft at opposite ends of the printing member and respectively engaging the friction surfaces, said friction members having peripheral surfaces adapted to coat with the impression roller 15 in feeding articles past the die; with means for arresting the die at the end of each rotation thereof, and article actuated means for releasing the die for each article passing the same, substantially as described.

25. In mechanism of the character specified, the combination of an impression roller and means for rotating same; a shaft beside the impression roller, and means for rotating the shaft; a die rotatably mounted on said 20 roller and provided with friction surfaces on its opposite ends, friction members attached to the shaft at opposite ends of the die and respectively engaging the opposed friction surfaces of the die, said friction 25 members having peripheral flanges adapted to coat with the impression roller in forwarding articles past the die; with means for stopping the die at each rotation thereof, and trip mechanism for releasing the die 30 each time an article is fed therewith.

26. In mechanism of the character specified, the combination of an impression roller, and means for rotating same; a shaft beside the impression roller; and means for rotating 35 the shaft; a die rotatably mounted on said roller and provided with friction disks on its opposite ends, friction members attached to the shaft at opposite ends of the die and frictional means interposed between the said 40 friction members and disks, said friction members having peripheral flanges adapted to coat with the impression roller in forwarding articles past the die.

27. In mechanism of the character specified, the combination of an impression roller, and means for rotating same; a shaft beside the impression roller; and means for rotating the shaft; a die rotatably mounted 45 on said roller and provided with friction 50 disks on its opposite ends, friction members attached to the shaft at opposite ends of the die and frictional means interposed between

the said friction members and disks, said friction members having peripheral flanges adapted to coat with the impression roller 55 in forwarding articles past the die; with means for regulating the pressure of the friction members against the disks, means for stopping the die at each rotation thereof, and article operated trip mechanism for releasing the die each time an article is fed therewith.

28. In mechanism of the character specified, the combination of a rotating impression roller, a printing member and friction 70 members at opposite ends of the printing member and continuously engaged therewith adapted to drive the printing member and coöperate with the roller in feeding articles past the printing member; with means for 75 arresting the printing member at each rotation thereof, and tripping mechanism located above the die for releasing the printing member, said tripping mechanism being actuated by articles fed toward the printing 80 member, substantially as described.

29. In mechanism of the character specified, a driven shaft, a printing member rotatably mounted thereon provided with a friction surface at each end; a pair of friction members attached to said shaft at opposite ends of the printing member and respectively continuously engaging the opposed friction surfaces, and means for yieldingly 90 pressing the friction members toward each 95 other to regulate the friction between the opposed friction surfaces; with means for arresting the printing member at each rotation thereof, and tripping mechanism located above the die for releasing the printing member, said tripping mechanism being 100 actuated by articles fed toward the printing member, substantially as described.

30. In mechanism of the character specified, an impression roller, a driven shaft beside the roller, a printing member rotatably mounted thereon provided with friction surfaces at opposite ends, friction members connected with said shaft and rotating therewith and engaging said surfaces to cause 105 the printing member to rotate, said friction members having circular peripheral flanges adapted to coat with the impression roller to feed articles past the printing member; with means for arresting the printing member 110 at each rotation thereof, and tripping mechanism located above the die for releasing the printing member, said tripping mechanism being actuated by articles fed toward the printing member, substantially 115 as described.

In testimony that I claim the foregoing as my own, I affix my signature.

WALTER H. BOWES.
